US0D1015166S

(12) **United States Design Patent** (10) **Patent No.:** **US D1,015,166 S**
Roffers et al. (45) **Date of Patent:** **** Feb. 20, 2024**

(54) **PACKAGING**

(71) Applicants: **Trilliant Food and Nutrition, LLC**, Little Chute, WI (US); **Horseshoe Beverage Company, LLC**, Neenah, WI (US)

(72) Inventors: **Brian Roffers**, Freedom, WI (US); **Mike Simon**, Hortonville, WI (US); **Shaylyn Wulderk**, Greenville, WI (US)

(73) Assignees: **Trilliant Food and Nutrition, LLC**, Little Chute, WI (US); **Horseshoe Beverage Company, LLC**, Neenah, WI (US)

(**) Term: **15 Years**

(21) Appl. No.: **29/804,112**

(22) Filed: **Aug. 18, 2021**

(51) LOC (14) Cl. **09-03**

(52) U.S. Cl.

USPC **D9/752**; D9/716

(58) **Field of Classification Search**

USPC D9/716, 721, 737, 751, 414, 418, 433

CPC B65D 71/50

CLAIM

The ornamental design for packaging, as shown and described.

DESCRIPTION

FIG. 1 is a top perspective view of a packaging; FIG. 2 is a bottom perspective view thereof;

FIG. 3 is a front elevation view thereof;
FIG. 4 is a rear elevation view thereof;
FIG. 5 is a right elevation view thereof;
FIG. 6 is a left elevation view thereof;
FIG. 7 is a top plan view thereof;
FIG. 8 is a bottom plan view thereof;
FIG. 9 is a cross-sectional view thereof taken along line 9-9
of FIG. 7;
FIG. 10 is a cross-sectional view thereof taken along line
10-10 of FIG. 7;
FIG. 11 is a top perspective view of a packaging according
to another embodiment;
FIG. 12 is a bottom perspective view of the packaging of
FIG. 11;
FIG. 13 is a front elevation view of the packaging of FIG.
11;
FIG. 14 is a rear elevation view of the packaging of FIG. 11;
FIG. 15 is a right elevation view of the packaging of FIG. 11;
FIG. 16 is a left elevation view of the packaging of FIG. 11;
FIG. 17 is a top plan view of the packaging of FIG. 11;
FIG. 18 is a bottom plan view of the packaging of FIG. 11;
FIG. 19 is a cross-sectional view of the packaging taken
along line 19-19 of FIG. 17; and,
FIG. 20 is a cross-sectional view of the packaging taken
along line 20-20 of FIG. 17.
The broken lines depict portions of the packaging in which
the design is embodied that are not considered part of the
claimed design.
